UNITED STATES PATENT OFFICE

157,220

CHILD'S SHOE

Sándor Weisz, Budapest, Hungary

Application November 20, 1948, Serial No. 149,730
In Hungary August 16, 1948

Term of patent 14 years

(Cl. D7—7)

To all whom it may concern:

Be it known that I, Sándor Weisz, a citizen of the Republic of Hungary, residing at Budapest, in the Republic of Hungary, have invented a new, original, and ornamental Design for a Child's Shoe, of which the following is a specification, reference being made to the accompanying drawing, forming part thereof.

The figure is a perspective view of a child's shoe, showing my new design, the opposite side presenting substantially the same appearance as the side shown.

I claim:

The ornamental design for a child's shoe, substantially as shown and described.

SÁNDOR WEISZ.
